UNITED STATES PATENT OFFICE.

GUSTAVE B. REISBACH, OF MILWAUKEE, WISCONSIN.

ELECTRIC SWITCH.

1,022,049.

Specification of Letters Patent.

Patented Apr. 2, 1912.

Application filed July 25, 1910. Serial No. 573,650.

To all whom it may concern:

Be it known that I, GUSTAVE B. REISBACH, a citizen of the United States, residing at Milwaukee, in the county of Milwaukee and

5 State of Wisconsin, have invented new and useful Improvements in Electric Switches, of which the following is a full, clear, concise, and exact description, reference being had to the accompanying drawing, forming 10 a part of this specification.

My invention relates to improvements in electric switches and particularly to blow out devices therefor.

One object of my invention is to provide, 15 in conjunction with an electric switch, a simple and efficient device for utilizing the magnetic lines of force produced by the current traversing the switch for extinguishing or disrupting the arcs produced upon operation of the switch.

A further object of my invention is to so arrange the blow out device that it may be bodily removed and replaced with ease and without in any wise disturbing the switch 25 mechanism.

My invention also has various objects and advantages, which will hereinafter be clearly and fully set forth.

For the purpose of more fully disclosing 30 my invention, I shall describe the device illustrated in the accompanying drawing, which embodies my invention in one form. It should be understood, however, that my invention is not limited to the particular 35 structure illustrated, but is susceptible of various modifications.

Figure 1 is a side elevation of the device. Fig. 2 is a sectional view taken on line 2—2 Fig. 3 and Fig. 3 is a sectional view taken 40 on line 3—3 Fig. 1.

The general structure of the switch, illustrated, is of conventional form and will therefore only be briefly described herein.

The various parts of the device are 45 mounted upon an insulating base 1. The base 1 supports a magnet frame 2 having a downwardly extending lug 3 which has its lower end secured to the base 1 by any suitable means such as the bolt 4. The magnet 50 frame 2 is also preferably secured to the base at other points; but the securing means has not been illustrated as it does not form an essential part of my invention. Pivotally mounted, upon a stud 5, carried by 55 the portion 3 of the magnet frame, is a

switch arm 6 carrying a laminated brush 7 and a spring pressed pivoted extension 8, upon the free end of which is mounted an arcing contact 9. The pivoted extension 8 is electrically connected to the arm 6 by a suitable flexible conductor 10, while the contact brush and the arm 6 are electrically connected to binding post 11 by a suitable flexible conductor 12. The switch arm, as illustrated, is formed in sections suitably insulated as shown at 14. With this arrangement, the current carrying portion of the arm is insulated from the magnet frame. The contacts 7 and 9 of the movable switch arm are adapted to engage stationary contacts 15 and 16 respectively. As illustrated, contact 15 merely comprises a flat plate secured to the insulating base by suitable means, such as a screw 17 and a bolt 18, the latter forming the second terminal of the switch. The plate 15 is provided with an upwardly projecting extension 19 slightly spaced from the base 1 and of suitable construction to receive and support the contact 16, which is in the form of a carbon block. 80 The operating means for the movable switch member comprises a solenoid 20 mounted in the magnet frame and having a movable plunger 21 connected to a lever 22 pivoted to a lug 23 on the magnet frame. The lever 85 22 is connected to the switch arm 6 by means of a link 24. This arrangement, in effect, forms a toggle connection which, when the solenoid 20 is energized, is operated to move the switch member 6 into engagement with 90 the stationary contacts. The arrangement of contacts is such that when the switch arm 6 is moved, the arcing contact 9 thereof will first engage the stationary carbon contact 16 and subsequently the laminated 95 brush 7 will engage the stationary contact plate 15. The movable contacts leave their respective stationary contacts in a reverse order.

The structure of the blow out device is as 100 follows: The several parts of the blow out device are carried by a magnetic plate which is bent or formed into a substantially U shape, thereby providing a pair of parallel pole pieces 30 and a connecting portion 105 31. Secured to the inner side of each pole piece 30, as by means of rivets 32, preferably of insulating material, is an insulating plate 33 preferably of greater dimensions than the pole piece. The insulating 110

plates may be formed of any suitable material. Asbestos boards may be used for this purpose. For holding the insulating plates and, consequently, the extremities of the 5 pole pieces in spaced relation, I have interposed between the insulating plates, a spacing block 34, which may conveniently be held in place by a bolt 35. In addition, I have interposed between the upper and rear 10 ends of the insulating plates, an obliquely disposed block 36, which may also be secured in place by any suitable means, such as bolts 37. The block 36 performs a two-fold function. First, it acts as a spacer for 15 the insulating plates 33. Second, it forms a shield against which the arc produced between the switch contact is blown, and, being obliquely disposed, forms a deflector for the arc. In view of the latter function 20 performed by the block 36, I prefer to form the same of some substantially insulating material, such as soap stone, but, of course, any other desired material may be employed therefor. It will thus be seen that the plates 25 33 and block 36 form an insulating chute or barrier, and that the blow out device is a substantially unitary structure which may be easily and conveniently handled. To mount this blow out device in place on the 30 switch, it is only necessary to insert the connecting portion 31 of the pole pieces between the carbon contact support and the insulating base 1, in which position the arc-ing contacts of the switch will be disposed 35 between the pole pieces 30. The method of attachment thus afforded enables the blow out device to be set in place and to be removed by a mere vertical movement thereof, without necessitating the operation of any 40 locking or securing means.

With the arrangement of contacts, illustrated, it will be seen that when the arc-ing contacts are in engagement and the laminated brush 7 is out of engagement with the 45 contact plate 15, the path of the current, through the switch, will be of a tortuous character. In other words, the arrangement of the arc-ing contact is such as to provide substantially half a turn between the 50 pole pieces 30 of the blow out device. This concentrates the magnetic lines of force produced by the current traversing the switch to such an extent that the lines of force will traverse the plates forming the pole pieces 55 of the blow out device and will produce a magnetic field, between the pole pieces, of such magnitude as to disrupt or extinguish any arc formed between the switch contacts. It will be seen that inasmuch as the pole 60 pieces of the blow out device are formed of a single plate they will produce a path of low magnetic reluctance, thereby insuring a strong magnetic field between the pole pieces.

65 Having thus described my invention,

what I claim as new and desire to secure by Letters Patent, is:

1. In an electric switch, in combination, a stationary contact and a coöperating movable contact, a magnetic plate supported and retained in place by one of said contacts and having substantially parallel extensions disposed on opposite sides of said contacts, the current traversing said contacts inherently producing a magnetic field between said extensions, and an insulating chute or barrier arranged between and supported by said extensions, said chute or barrier having an obliquely disposed arc deflector. 70

2. In an electric switch, in combination, a stationary contact and a coöperating movable contact, a magnetic plate supported by one of said contacts and having substantially parallel extensions disposed on opposite sides of said contacts, the current traversing said contacts inherently producing a magnetic field between said extensions, and an insulating chute or barrier arranged between and supported by said extensions, said chute or barrier having an obliquely disposed arc deflector, said magnetic plate and said chute or barrier being removable from the switch as an integral structure and being retained in place solely by its engagement with said stationary contact. 80

3. In an electric switch, in combination, a stationary contact and a coöperating movable contact, a magnetic plate supported by one of said contacts and having substantially parallel extensions disposed on opposite sides of said contacts, the current traversing said contacts inherently producing a magnetic field between said extensions, and an insulating chute or barrier arranged between and supported by said extensions, said chute or barrier having an obliquely disposed arc deflector, said magnetic plate and said chute or barrier being adapted to be removed from the switch as an integral structure and to be retained in place solely by its engagement with said stationary contact, said magnetic plate having a sliding engagement with said contact. 90

4. In an electric switch, in combination, vertically disposed coöperating switch contacts, a magnetic plate fitting between one of said contacts and its supporting member and having substantially parallel extensions disposed on opposite sides of said contacts, the current traversing said contact inherently producing a magnetic field between said extensions, and insulating plates secured to the inner faces of said extensions to form an insulating chute or barrier, said plates being of greater dimensions than said extensions. 100

5. In an electric switch in combination, coöperating contacts, one of said contacts being stationarily mounted and provided with a recessed portion, a magnetic plate 110

fitting in the recessed portion of said stationary contact and supported by said contact, said magnetic plate having substantially parallel extensions disposed on opposite sides of said coöperating contacts, the current traversing said contact inherently producing a magnetic field between said extensions to extinguish arcs drawn between said contacts, and insulating plates secured 10 to the inner faces of said extensions to form an insulating tube or barrier.

6. In an electric switch, in combination, a supporting base, a stationary contact carried thereby, a coöperating movable contact, 15 a magnetic plate arranged to slide between said stationary contact and said supporting base, said magnetic plate having substantially parallel extensions disposed on opposite sides of said contacts, the current traversing said contacts inherently producing a magnetic field between said extensions and an insulating chute or barrier arranged between and supported by said extensions, said insulating chute or barrier having an obliquely disposed arc deflector, the side 20 walls of said insulating chute or barrier being of greater dimensions than said extensions.

25 In witness whereof, I have hereunto subscribed my name in the presence of two witnesses.

GUSTAVE B. REISBACH.
